UNITED STATES PATENT OFFICE.

GEORGE R. FIELDS, OF TERRE HAUTE, INDIANA, ASSIGNOR TO THE FIELDS COMPANY,
A CORPORATION OF INDIANA.

METHOD FOR COOKING CATSUP AND LIKE PRODUCTS.

1,113,110.

Specification of Letters Patent.

Patented Oct. 6, 1914.

Application filed February 2, 1914. Serial No. 816,118.

To all whom it may concern:

Be it known that I, GEORGE R. FIELDS, a citizen of the United States, residing in Terra Haute, in the county of Vigo and State of Indiana, have invented a new and useful Method for Cooking Catsup and like Products, of which the following is a specification.

My invention relates to a method whereby 10 tomato-pulp catsup, syrup and like products may be thoroughly reduced and cooked in large quantities, and the objects of the invention are: first, to provide a method whereby the pulp or stock from which catsup, or other similar commodity, may be 15 thoroughly reduced and cooked, in large quantities, in a minimum length of time, and at a minimum expense, in labor and cost; second, to provide such a method 20 whereby large quantities of stock may be reduced and cooked without danger of burning, scorching or otherwise injuring the product, and, third, to furnish such a method, whereby catsup, or other like products, may be reduced and cooked in a sanitary, safe and economical manner.

These objects I attain by means of the method hereinafter described, and the mechanism illustrated in the accompanying 30 drawings, in which,

Figure 1 is an elevation of the tank, shown partially in section, to expose interior. Fig. 2 is a plan of an apparatus suitable for carrying out my process.

Similar letters of reference refer to similar parts throughout the several views.

The apparatus necessarily used to cook catsup by my process consists of a large tank A, open at the top and provided with a 40 floor, which is inclined from the back of the tank toward the front thereof, as shown in Fig. 1. The inclination of the floor *f* is an essential feature, in the construction of the apparatus and in the process, as more fully 45 set forth hereinafter. A pair of large, acid-proof, seamless tube coils, C and C', one within the other, are erected within the tank A, and supported upon a plurality of metallic, acid-proof stays, or standards S. The 50 standards S are soldered firmly to the coils and all recesses between stays and coils are carefully filled with solder, or other suitable material, for the purpose of removing all possible danger of stock, or other material, 55 entering and lodging therein. All metal

work is thoroughly tinned with pure tin, to prevent impurities from forming, by reason of the acids in the stock. The coils C and C' are connected at the upper, or intake extremities, with steam supply-pipes, P and P' 60 respectively, and the lower or discharge extremities of the coils are connected with discharge pipes, *p* and *p'* which pass through the floor *f* of the tank A. The discharge pipes, *p* and *p'*, are connected by a pipe *q*, 65 which is furnished with a pendent drain valve *r*. The connected discharge pipes have connection with an exhaust pipe *t*. One or more suitable valves V, preferably of sliding stem type, are mounted upon the outside of 70 the tank A, in fluid-passage connection with corresponding discharge vents W, one or more, of which are provided at the lowest possible point, or points, of the floor *f*, as shown in Fig. 1. The tank is mounted upon 75 substantial supports X, of sufficient elevation to permit free passage of all discharge and exhaust connections.

My process consists in the thorough pulping of the tomato stock and the introduction 80 of the pulp in large quantities into the tank A, where the pulp covers the coils C and C'. The drain-valve *r*, is then closed and steam is admitted into the coils C and C', through the supply-pipes P and P'. The steam so 85 admitted follows the special course of the coils, thereby heating the coils, from which intense heat is diffused in all directions throughout the bulk of pulp, in which the coils are immersed. Small quantities of 90 cold water are dashed upon the cooking pulp to prevent foaming, and a proper degree of heat is maintained for a proper length of time, to thoroughly reduce and cook the pulp to a finished catsup, or other like product. The steam is then cut off from the 95 supply-pipes and the drain-valve is opened to drain off all condensation from the coils. The finished catsup is reduced to a liquid condition and tends to reach the lowest possible level, thereby forcing itself by gravitation to freely discharge through the discharge valve V, when the same is opened.

The advantages claimed for my process, 100 as carried out by means of the apparatus described, consist; first, in the exceedingly large amount of stock which may be thoroughly cooked at one heat; second, in the absolute security against burning or scorching the catsup and the absence of danger 105

from contamination from old stock, acids or other similar impurities, commonly experienced in the cooking of catsups, by other methods used prior hereto; and, third, in 5 the increased degree of economy attained by reason of the economical construction and operation of the apparatus and the large saving in steam expense attained by reason of the improved manner of distributing and 10 applying the heat.

When tomato catsup first boils, the coloring matter, which is lighter than the pulp, rises to the top and unless some means is provided for checking the boiling over of the 15 pulp, a large part of the natural coloring matter will be lost. By spraying water, or other suitable liquid over the pulp when the same is boiling, the natural coloring matter will be carried down into the pulp and also 20 the boiling over will be checked. In this way the spraying of a cooling liquid upon the boiling pulp has the twofold result of

25 checking boiling over of the pulp and retaining the natural coloring matter of said pulp.

I claim:

1. A process of cooking tomato catsup consisting in thoroughly pulping the stock, introducing the same into an open wooden tank so that the same is under atmospheric 30 pressure, introducing a diffusing heat into all parts of the stock from within the tank, and spraying said stock when the coloring matter rises in said tank, with a cooling liquid.

2. The process of preventing the boiling over of catsup pulp and the escape of coloring matter contained therein which consists in spraying the boiling pulp with a cooler liquid.

35 GEORGE R. FIELDS.
